W. CLEMENS.

LIFTING JACK.

APPLICATION FILED JAN. 6, 1919.

1,298,895.

Patented Apr. 1, 1919.

WILLIAM CLEMENS-
BY
Hazard E. Miller
ATTORNEYS

UNITED STATES PATENT OFFICE.

WILLIAM CLEMENS, OF SAN FERNANDO, CALIFORNIA.

LIFTING-JACK.

1,298,895.

Specification of Letters Patent.

Patented Apr. 1, 1919.

Application filed January 6, 1919. Serial No. 269,861.

To all whom it may concern:

Be it known that I, WILLIAM CLEMENS, a citizen of the United States, residing at San Fernando, in the county of Los Angeles and 5 State of California, have invented new and useful Improvements in Lifting-Jacks, of which the following is a specification.

My invention relates to lifting jacks and more particularly to a lifting jack adapted 10 to be suspended from a derrick or overhead beam.

An object of my invention is to provide a lifting jack suitable for lifting objects which are normally at some distance from the 15 ground, such as wagon beds and the like.

With this and other objects in view, my invention consists in the construction, combination and arrangement of parts herein shown, described and claimed.

20 In the accompanying drawings, which form a part of this specification,

Figure 1 is a side elevation showing a lifting jack embodying the principles of my invention suspended to an over-head beam, 25 parts being broken away to show the construction.

Fig. 2 is an enlarged sectional detail on the line 2—2 of Fig. 1.

Fig. 3 is an enlarged sectional detail on 30 the line 3—3 of Fig. 1 showing the connections of the links with the lever and showing the spring which acts to hold the catch pins against the rack bar.

Fig. 4 is a fragmentary edge view looking 35 in the direction indicated by the arrow 4 in Fig. 1.

Fig. 5 is a view analogous to Fig. 1 and showing a different operation.

Referring to the drawings in detail, a supporting frame 1 has a hook 2 attached to its 40 upper end and the hook 2 is suspended from a beam 3 by a cable 4. The supporting frame 1 is made up of a wide middle bar 5 which serves as a rack bar and the outer 45 guide bars 6 and 7, there being spaces 8 and 9 between the guide bars and the rack bar. The rack bar 5 has a series of rounded and 50 upwardly turned notches in each of its sides 10 and 11, said notches being staggered with reference to each other, so that a notch on one side is midway between two notches on the opposite side. A link 12 is formed of

parallel bars 13 and 14, the lower ends of the bars being connected to a hand lever bar 15 by a pivot bolt 16. The upper ends of 55 the link bars are connected by a catch pin 17 which holds the bars spaced apart, so that the catch pin 17 will engage in the notches 11, and so that the bars 13 and 14 will work freely in opposite sides of the rack bar 5. A 60 similar link 18 consists of two bars connected to the hand lever bar 15 by a bolt 19 with a catch pin 20 at its upper end to engage in the notches 10. A retractile coil spring 21 has its ends attached to the links 65 12 and 18 a short distance above the hand lever bar 15 by bolts 22 and 23, the tension of the spring being exerted to hold the links 12 and 18 to press the catch pins 17 and 20 into the notches 10 and 11. The spaces 8 70 and 9 between the guide bar 6 and the rack bar 5, and the rack bar 5 and the guide bar 7 are large enough to allow the free passage of the catch pins as they move upwardly and downwardly out of the notches 10 and 11. 75

A hook 24 is pivotally connected to the hand lever bar 15 half way between the bolts 19 and 16, and the hook 24 is adapted to carry the load to be lifted. The ends 25 and 26 of the hand lever bar 15 are round, so 80 that pipe extensions may be slipped over the ends 25 and 26 and used as operating handles. A throw-off lever 27 is connected to the bar 13 by a cap screw pivot 28 extending loosely in the intermediate portion of the lever. A 85 handle 29 extends outwardly from the long end of the lever 27, and a tongue 30 extends inwardly from the short end of the lever. The lever is bent in side elevation so that the long end 31 hangs downwardly from the 90 pivot 28, and the short end 32 extends upwardly and laterally from the pivot nearly at a right angle. The tongue 30 of the throw-off lever 27 engages the inner edge of one of the bars of the link 18. An operating cord 33 is connected to the handle 29. When the cord 33 is released the long end 31 of the throw-off lever 27 will hang downwardly and swing freely upon the pivot 28. 95

The jack thus constructed may be operated 100 from either end of the hand lever bar 15 or from both ends simultaneously, and as the hand lever bar is vibrated up and down the links 12 and 18 will alternately raise and

lower, and the catch pins 17 and 20 will alternately carry the load, and the load will be raised or lowered step by step.

Assuming that the hand lever 15 is being operated from the right-hand end, as shown in Fig. 1, the pipe extension is slipped over the round end 26, and the pipe extension is omitted from the other end. Upward movement of the handle will bring the link 18 into position with the catch pin 20 in the notch 10, and the catch pin will support the load while the link 12 moves upwardly until the catch pin 17 moves into the next notch 11. During this operation the pivot bolt 19 is the fulcrum of the hand lever 15. Downward movement of the handle will then throw the load upon the catch pin 17 and the pivot bolt 16 becomes the fulcrum of the hand lever 15. This action will cause the link 18 to move upwardly until the catch pin 20 engages the next higher notch and so on. Thus by alternately raising and lowering the handle and vibrating the hand lever 15 the catch pins 17 and 20 alternately move upwardly into the next higher notches and the load is raised.

When it is desired to lower a load with the parts in the position shown in Fig. 1, the handle will be depressed enough to release the catch pin 20 from supporting the load, then the cord 33 will be pulled to operate the throw-off lever 27 to push the tongue 30 against the link 18, thereby moving the link 18 to move the catch pin 20 into the space 8 clear of the rack bar; then the handle will be operated to lower the catch pin 20 to the next notch below, and the cord 33 released, then the operation of the handle will be continued to throw the load upon the catch pin 20, then the cord 33 will be pulled to throw the catch pin 17 out of the notch and the handle will be operated to lower the catch pin 17 to the next notch as shown in Fig. 5 and this operation is continued to lower the load step by step.

Various changes may be made without departing from the spirit of my invention as claimed.

I claim:

50 1. A lifting jack comprising, a suspended supporting bar, said supporting bar consisting of a middle two edged rack bar and two parallel guide bars in spaced relation to the edges of the rack bar; a catch acting along and in engagement with each of the two notched edges of said rack bar between said guide bars and said rack bar; a lever adapted to be operated at either end; links operatively connecting said catches to said lever bar; means for suspending said supporting bar; and means for attaching the load to said lever bar.

2. A lifting jack comprising, a suspended supporting bar consisting of a middle two

edged rack bar and two parallel guide bars 65 in spaced relation to the edges of said rack bar; catch pins acting along the edges and in engagement with the notches in said rack bar; a lever bar adapted to be operated at either end; links in the upper ends of which 70 said catch pins are fixed and the lower ends of which are pivoted to said lever bar in spaced relation to each other; a retractile spring having one end fixed to each of said links and adapted to pull said catch pins 75 fixed in the upper ends of said link into the notches in said rack bar; means for suspending said supporting bar; and means for attaching the load to said lever bar.

3. A lifting jack comprising, a suspended 80 supporting bar, said supporting bar consisting of a middle two edged rack bar and two parallel guide bars in spaced relation to the edges of the rack bar; a catch acting along and in engagement with each of the two 85 notched edges of said rack bar between said guide bars and said rack bar; a lever bar adapted to be operated at either end; links operatively connecting said catches to said lever bar; means for suspending said supporting bar; means for attaching the load to said lever bar; and a throw-off lever pivotally connected to one link and adapted to engage the other link.

4. A lifting jack comprising, a suspended 95 supporting bar consisting of a middle two edged rack bar and two parallel guide bars in spaced relation to the edges of said rack bar; catch pins acting along the edges and in engagement with the notches in said rack 100 bar; a lever bar adapted to be operated at either end; links in the upper ends of which said catch pins are fixed and the lower ends of which are pivoted to said lever bar in spaced relation to each other; a retractile 105 spring having one end fixed to each of said links and adapted to pull said catch pins fixed in the upper ends of said link into the notches in said rack bar; means for suspending said supporting bar; means for attaching the load to said lever bar; and a throw-off lever pivotally connected to one link and adapted to engage the other link to hold one 110 catch pin out of engagement while the other is in engagement.

5. A lifting jack comprising, a suspended supporting bar, said supporting bar consisting of a middle two edged rack bar and two parallel guide bars in spaced relation to the edges of the rack bar; a catch acting along and in engagement with each of the two notched edges of said rack bar between said guide bars and said rack bar; a lever bar; links operatively connecting said catches to said lever bar; means for suspending said supporting bar; and means for attaching the load to said lever bar.

6. A lifting jack comprising, a suspended

supporting bar, said supporting bar consisting of a middle two edged rack bar and two parallel guide bars in spaced relation to the edges of the rack bar; a catch acting along 5 and in engagement with each of the two notched edges of said rack bar between said guide bars and said rack bar; a lever bar; links operatively connecting said catches to

said lever bar; means for suspending said supporting bar; means for attaching the 10 load to said lever bar; and means for operating the catches to step the load downwardly.

In testimony whereof I have signed my name to this specification.

WILLIAM CLEMENS.
